WELL DRILLING APPARATUS

James A. Lupfer, Tulsa, Okla.

Application March 16, 1934, Serial No. 715,880

5 Claims. (Cl. 255—19)

This invention relates to well drilling and more particularly to a method and apparatus for use in drilling deep wells for oil, water, or the like, using a rotary drill bit, which apparatus and method will reduce the cost of such drilling operations through the reduction of the quantity of machinery employed without reducing the speed or efficiency of drilling.

An object of the present invention is to provide a reversible hydraulic turbine for operating the draw-works or elevating apparatus employed in the drilling rig and to utilize the slush pumps to supply liquid under pressure for operating the hydraulic turbine.

Another object of the invention is to provide a pumping layout for a drill rig whereby the pumps may be utilized to pump the slush to the drill bit or by manipulation or adjustment of suitable valves they may be employed to pump clear water for operating the hydraulic turbine; and also to provide suitable relief lines to permit flushing of the pressure liquid line at desired times.

Other objects of the invention are: to provide relief valves in the pressure line between the pumps and turbine which will prevent excessive and dangerous pressure rise in the pressure lines; the use of pressure equalizers in the pressure line for leveling out unevenness in the liquid flow; means for varying the speed and torque developed by the reversing hydraulic turbine and the provision of a compact efficient apparatus for well drilling wherein a minimum number of mechanisms are employed to provide a maximum number of operations, and an apparatus or layout wherein a minimum number of prime movers are employed to perform the required amount of work.

With these and other objects in view as may appear from the accompanying specification, the invention consists of various features of construction and combination of parts, which will be first described in connection with the accompanying drawings, showing a well drilling apparatus of the preferred form, and the features forming the invention will be specifically pointed out in the claims.

In the drawings:

Fig. 1 is a diagrammatic plan of the improved well drilling apparatus.

Fig. 2 is a side elevation of the improved well drilling apparatus.

Fig. 3 is a side elevation of the improved reversible hydraulic turbine employed on the well drilling apparatus.

Fig. 4 is a vertical section through the turbine taken on the line 4—4 of Fig. 3.

Fig. 5 is a fragmentary vertical section through the turbine showing the operating-flow directing quadrant in turbine non-operating position. 5

Fig. 6 is a view similar to Fig. 5 showing the quadrant in position for operating the turbine in a direction reverse to its normal direction of operation.

Fig. 7 is a plan view of the operating fluid directing nozzle and quadrant. 10

Fig. 8 is a view partly in plan of the nozzle and quadrant showing the guiding hood broken away.

Fig. 9 is a horizontal section through the turbine rotor taken on the line 9—9 of Fig. 4. 15

Fig. 10 is a section through the operating fluid guiding quadrant taken on the line 10—10 of Fig. 4.

Referring more particularly to the drawings, 20 the improved well drilling apparatus comprises a rotary drilling rig 1 of any approved type which can be purchased upon the open market and is now commonly in use for drilling deep wells for oil or the like. In rotary drilling rigs 25 of this type, a rotary drilling bit is provided for the drilling operation, and slush in the form of water, mud or the like, is pumped down through the drill pipe to the bit to facilitate the drilling operation and to wash out the bit cuttings from 30 the hole being drilled. In the drawings, this drilling rig is only shown diagrammatically since it is a well known structure. The drilling rig is raised from the well by the draw-works or elevating apparatus of any approved type such as 35 shown at 2 in Figs. 1 and 2 of the drawings. In the present invention, the elevating apparatus 2 is operated by a reversible hydraulic turbine 3 which will be specifically described hereafter and in connection with Figs. 4 to 10 inclusive 40 of the drawings. In Fig. 1 the turbine 3 is shown connected to the elevating apparatus 2 through a speed reducer mechanism 4, but it is to be understood that it may be connected in any suitable manner to the elevating apparatus, such as either directly connected, or connected by means of gears, chain or belt connection without departing from the spirit of the present invention. 45

The hydraulic turbine is operated by pressure 50 fluid pumped by the same pumps which supply the slush to the rotary drilling rig 1. In Fig. 1 of the drawings a plurality, namely three of these pumps, is shown at 5, 6 and 7. All of the pumps 5, 6 and 7 are direct acting reciprocating 55

ing pumps of approved type particularly designed for the handling of gritty or dirty water such as comprises the slush used in drilling. Each pump has a prime mover direct connected thereto as indicated at 8, 9 and 10 respectively. In the drawings these prime movers are shown as internal combustion engines but any suitable type of prime mover such as steam engines, electric motors, or the like, may be employed in lieu of the internal combustion engines without departing from the spirit of the present invention.

The suction ports (not shown) of each of the pumps 5, 6 and 7 are connected by a suitable pipe 11, 12 or 13 to a clear water intake manifold which in turn has connection through a suitable supply pipe 15 with a source of supply of clear water. Pipes 16, 17 and 18 are also connected to the pump suction and these pipes are connected to a manifold 19 which has inlet connection through a pipe 20 with the slush pit as indicated at 21. Valves 22 and 23 are mounted one in each of the clear water inlet pipes 11, 12 and 13, and one in each of the slush inlet pipes 16, 17 and 18, so that by adjustment of these valves the pump suction may be connected either to the clear water intake manifold for pumping clear water or to the slush intake manifold 19 for pumping slush, depending on whether it is desired to operate the rotary drilling rig 1 or the reversible hydraulic turbine 3.

Pumps 5, 6 and 7 discharge through discharge pipes 24, 25 and 26 into a discharge line 27 and valves 28 are provided in the discharge line adjacent to the connection of the discharge line 27 with each of the respective discharge pipes 24, 25 and 26, so that if it is desired the directional flow of the pump discharge in the discharge line 27 may be regulated by regulation of these valves 28, or if it is desired the discharge of one or more of the pumps through the discharge line 27 to the rotary drilling rig 1 may be cut off by adjustment of these valves 28.

The discharge line 27 is connected through a suitable standpipe 29 and pipe and hose connection 30 to the rotary drilling rig 1. A pressure equalizer 31, which may be of any approved type such as that shown in my companion application Serial Number 615,346, is connected to the discharge line 27 between the connections of the discharge line with the pump discharges and the drilling rig 1 for the purpose of leveling out or evening pulsations in the flow of fluid to the rotary drilling rig.

A relief line 32 having a relief valve 33 therein is connected to the discharge line outwardly of the standpipe 29 so as to permit the bleeding off of pressure fluid from the discharge line for the purpose of flushing the discharge line if desired. Also the relief valve 33 may be of any approved type of automatic relief valve which can now be purchased upon the open market and operable to prevent dangerous pressure rise in the pressure or discharge line 27.

The discharge line 27 is also connected to the inlet nozzle 35 of the reversible hydraulic turbine 3 so that when it is desired to operate the turbine, clear water may be pumped by any one or all of the pumps 5, 6 or 7 to supply the operating fluid to the turbine. A pressure equalizer 36 is connected to the discharge line between the connection of the discharge line 27 with the various pump discharges and its connection with the turbine inlet nozzle 35. This pressure equalizer 36 may be of any approved type, preferably such as that shown in my companion application above

mentioned, and it serves to level out the pulsations in the operating fluid for the turbine. A second relief line 37 and relief valve 38 are provided and connected to the discharge line 27 adjacent to its connection to the turbine 3, this line and valve serving to permit flushing of the discharge line and also to prevent the formation of dangerous pressure rises in the discharge line.

The operating fluid for the turbine 3 leaves the casing 40 of the turbine through the discharge pipe 41 and this discharge line 41 has a pipe 42 leading to the slush pit 21 and a second branch pipe 43 leading to the clear water pit or supply (not shown). Suitable valves 44 and 45 are provided whereby the discharge water from the turbine may be delivered either to the slush pit or to the clear water supply as desired.

From the foregoing description taken in connection with Figs. 1 and 2 of the drawings, it will be apparent that the drilling rig has been provided wherein the usual slush pumps such as shown at 5, 6 and 7 serve not only the purpose of pumping slush for the rotary drilling rig 1, but also serve to pump operating fluid for operating the reversible hydraulic turbine, thereby materially reducing the quantity of machinery necessary in the proper drilling of a deep well as well as provide a reversible hydraulic turbine which is cheaper in construction and operation than the usual type of prime-movers employed for operating the elevating apparatus 2. The provision of the reversible hydraulic turbine 3 is a vital part of the present invention since it is necessary to provide reversibility for the proper operation of the elevating apparatus 2.

The reversible hydraulic turbine comprises the casing 40 in which is mounted the rotor 46 keyed or otherwise suitably connected to the shaft 47 for rotating the shaft and through the shaft, the speed reducer 4.

The rotor 46 has a plurality of sets of buckets 48 connected thereto at spaced points about its periphery. Each set 48 comprises divided buckets 49 and 50 which open in opposite directions and are cupped to receive the operating jet of operating liquid for the purpose of rotating the rotor. The operating jet of liquid, indicated at 51 in Fig. 4 of the drawings is forced through the inlet nozzle 31 and the variation of speed and torque developed by the hydraulic turbine can be regulated by adjustment of the needle valve 52 in the nozzle 35, also the speed and torque developed by the turbine and variation of such speed can be accomplished by the variation in the speed of operation of the pumps 5, 6 and 7 or by the number of these pumps which are permitted to operate to supply operating fluid for the turbine and also by manipulation of the relief valve 33 to vary the volume of the liquid delivered to the jet or inlet nozzle 35 of the turbine. Normally, the incoming jet of operating water as indicated at 51 will strike within the buckets 49 for rotating the rotor in the direction indicated by the arrow "A" in Fig. 4 of the drawings.

When it is desired to reverse the direction of rotation of the rotor 46, the jet guiding quadrant 53 is rotated by means of its rotating lever 54 into the position shown in Fig. 6 of the drawings. When the quadrant 53 is positioned as shown in Fig. 6 of the drawings it will receive the incoming jet 51 of operating fluid into the opening 55 and the jet will travel through the diverging passageways 57 in the quadrant and engage in the spaced buckets 50 which are opposed to the buckets 49 and consequently the rotor 46 will be rotated in

the direction indicated by the arrow "B" in Fig. 6 of the drawings or in the direction reversely to its direction of rotation when the jet of operating liquid strikes the buckets 49.

5 When it is desired to stop the rotation of the rotor 46 during the supplying of operating liquid to the turbine, the quadrant 53 is moved into the position indicated in Fig. 5 of the drawings and when in such position it will guide the incoming 10 jet of operating water or liquid against the arcuate guiding which will direct the incoming operating fluid into the bottom of the casing 40 of the turbine from which it passes outwardly through the outlet 60 to the discharge pipe 41. Thus by 15 the simple adjustment of the position of the directing quadrant 53, the direction of rotation of the rotor may be reversed or stopped irrespective of the manipulation of any valve in the discharge line 27 or of the operation of any or all of 20 the pumps 5, 6 or 7.

It will be understood that the invention is not to be limited to the specific construction or arrangement of parts shown, but that these may be modified widely within the invention as defined 25 by the claims.

What is claimed is:

1. In a well drilling apparatus, the combination with a drilling rig, of a direct acting pump for pumping slush to said rig, a clear water supply 30 pipe connected to the suction of said pump, a slush standpipe connected to the discharge of the pump, valves in said pipes whereby either clear water or slush may be pumped, elevating means for raising said rig, a prime mover for operating 35 said elevating rig, and means whereby said prime mover may be operated by fluid pumped by said pump.
2. In a well drilling apparatus, the combination with a drilling rig, of a direct acting pump for pumping slush to said rig, an elevating apparatus 40 for raising said rig, a clear water supply pipe connected to the suction of said pump, a slush supply pipe connected to the pump suction, valves in said pipes whereby either clear water or slush 45 may be pumped, a hydraulic turbine for operating said elevating apparatus, said turbine connected to the discharge of said pump whereby the turbine may be operated by fluid pumped by the pump.
3. In a well drilling apparatus, the combination 50 with a drilling rig, of a plurality of pumps for pumping slush to said rig, an independent prime mover for each of said pumps, a plurality of supply pipes connected to the suction of each 55 pump, one of the supply pipes connected to each pump being connected to a slush supply source and another of said pipes connected to each pump being connected to a clear water supply source, and valves controlling said pipes to control the kind of liquid pumped, a discharge line

connected to the discharge of said pumps, said discharge line connected to said drilling rig for delivering slush pumped to the drilling rig, a hydraulic turbine connected to said discharge line for receiving clean water pumped, and valves in 5 said discharge line for controlling the flow of fluid therethrough.

4. In a well drilling apparatus, the combination with a drilling rig, of a plurality of pumps for pumping slush to said rig, an independent prime 10 mover for each of said pumps, a plurality of supply pipes connected to the suction of each pump, one of the supply pipes connected to each pump being connected to a slush supply source and another of said pipes connected to each 15 pump being connected to a clear water supply source, and valves controlling said pipes to control the kind of liquid pumped, a discharge line connected to the discharge of said pumps, said discharge line connected to said drilling rig for 20 delivering slush pumped to the drilling rig, a hydraulic turbine connected to said discharge line for receiving clean water pumped, and valves in 25 said discharge line for controlling the flow of fluid therethrough, said pumps having independent 30 connection with said discharge line, and a valve in said discharge line adjacent to its connection with each of the pump discharges whereby the directional flow through the discharge line of the liquid pumped by each pump may be controlled.

5. In a well drilling apparatus, the combination with a drilling rig, of a plurality of pumps for pumping slush to said rig, an independent prime mover for each of said pumps, a plurality 35 of supply pipes connected to the suction of each pump, one of the supply pipes connected to each pump being connected to a slush supply source and another of said pipes connected to each 40 pump being connected to a clear water supply source, and valves controlling said pipes to control the kind of liquid pumped, a discharge line connected to the discharge of said pumps, said discharge line connected to said drilling rig for 45 delivering slush pumped to the drilling rig, a hydraulic turbine connected to said discharge line for receiving clean water pumped, and valves in 50 said discharge line for controlling the flow of fluid therethrough, said pumps having independent connection with said discharge line, and a valve in said discharge line adjacent to its connection with each of the pump discharges whereby the directional flow through the discharge line of the liquid pumped by each pump may be controlled, relief lines connected to said discharge line and relief valves in said relief lines whereby 55 said discharge line may be flushed without the flushing liquid passing either to said drilling rig or turbine.

JAMES A. LUPFER.
